UNITED STATES PATENT OFFICE.

HENRY MARTIN SCOVEL, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed November 14, 1919. Serial No. 338,085.

This invention relates to hydrocarbon motors and more particularly to the construction of cylinder units and to the various parts of built up cylinders.

One of the objects of the invention is to provide a novel jacketed cylinder unit of light weight and of great strength.

Another object is to provide a unit having a water jacket, cylinder barrel and cylinder head assembled and connected together in a novel and efficient manner.

Another object is to provide a cylinder unit with a cylinder head in which the various parts are formed integral with the head, thereby forming a strong and rigid construction.

Other objects will appear from the following description taken in connection with the drawings, in which:

20 Fig. 1 is a vertical, longitudinal section, partly broken away, illustrating a complete cylinder unit, made in accordance with my invention;

Fig. 2 is a plan view of the cylinder head part of the unit shown in Fig. 1;

Fig. 3 is a side elevation of the head shown in Fig. 2;

Fig. 4 is an elevational view taken at right angles to Fig. 3;

30 Fig. 5 is an enlarged detail sectional view illustrating the manner of connecting the cylinder head to the barrel;

Fig. 6 is a plan view of one of the bracing members for the valve stem guiding means;

35 Fig. 7 is a longitudinal sectional view of the member shown in Fig. 6, and

Fig. 8 is an enlarged detail view in section, illustrating the construction of the valve stem guiding means and lug to which this

40 guiding means is connected and with respect to which it is braced.

My improved cylinder unit comprises a forged cylinder barrel and a forged cylinder head welded to the barrel, the cylinder head having forged integral therewith inlet and exhaust elbows and valve stem guiding members. The combustion chamber is also forged integral with the cylinder head and is provided with means for receiving the spark plugs. The cylinder head forging also is provided with upwardly extending lugs for supporting the valve shaft housing, these lugs also receiving bracing members which are connected to the valve stem guiding mem-

bers to prevent these members from spreading. The various parts of the cylinder barrel and cylinder head are provided with rims or flanges to which the water jacket is welded. This construction is described more fully hereinafter.

Referring to the drawings, I have illustrated in Fig. 1 a complete cylinder unit adapted to be used as a part of a hydrocarbon motor. This cylinder unit is of the overhead valve type and it will be understood that the cylinders may be built up separately or in pairs or a plurality of cylinders in the block as desired for the particular conditions under which they are used.

The cylinder barrel 10 is preferably made of a steel forging machined both inside and outside and formed with a flange 11 for the purpose of attaching the cylinder to the crank case or to an adjacent cylinder. A flange 12 is provided adjacent the upper end of the barrel, this flange being adapted to be welded to an outwardly extending peripheral flange 13 formed on the lower end of the cylinder head 14 which is superposed upon the barrel and is welded thereto as shown at 15. In order to properly position the head 14 on the barrel 10 an annular recess 16 is formed in the lower edge of the head and this recess is adapted to receive the upper, outer edge of the cylinder barrel, the flanges 12 and 13 being spaced apart sufficiently to expose a large surface for welding.

The cylinder head is formed from a single drop forging and the lower portion has formed therein a combustion chamber 17 having diametrically opposed bosses 18 which are screw threaded as shown at 19 and are adapted to receive spark plugs. The cylinder head forging also includes an intake elbow 20 and an exhaust elbow 21, tubular valve stem guiding members 22 being also forged integral with the cylinder head and intake and exhaust elbows. Suitable means is provided for bracing members 22 against possible displacement, due to the pressure or heat within the cylinder and this bracing means includes a pair of upwardly and outwardly extending lugs 23 forged integral with the cylinder head and on opposite sides thereon. These lugs are positioned adjacent the valve stem guiding members 22 and are connected to these members through bracing members 24, the members 24 being welded

to the lugs 23 and to the valve stem guiding members. The lugs 23 also serve as supports for the cam shaft housing.

This cylinder head forging is made by 5 two counter-part dies which take the form of the device shown in Figs. 3 and 4, the dies being divided substantially on the section of Fig. 1. It will be understood, of course, that in the rough forging the intake and 10 exhaust elbows will be solid and there will be a substantial amount of metal between the bosses 23 and their respective elbows, to provide for the usual draught in forging. This excess metal will later be machined 15 off as will also the interior of the elbows be machined. The brace 24 is formed as a separate piece as is clearly described above. When the elbows are machined the valve stem guiding members 22 are formed of the 20 re-entrant shape shown so that when the water jacket is in place there will be a substantial water space around the guiding members.

The water jacket is mounted on the cylinder unit just described by welding the jacket to a plurality of flanges or ribs in the following manner. An annular rib 25 is formed on the barrel 10 and flanges or ribs 26 are formed on the bosses 18. The outwardly extending tubular portions 27 of the intake and exhaust elbows are also provided with flanges 28 and annular ribs or flanges 29 are formed on the bracing member 24 and surround the apertures through 35 which extend the lugs 23 and valve stem guiding members 22. The water jacket is provided with suitable apertures for the reception of the bosses 18, outer ends 27 of the elbows and the outer ends of the valve stem 40 guiding members 22 and also the lugs 23 and after the jacket has been placed over these parts the portions of the jacket surrounding the flanges or ribs just described are welded thereto.

It will thus be seen that the cylinder unit 45 comprises the two forgings, namely the cylinder barrel and the cylinder head, and the welded on jacket. The forgings are welded together after which the jacket is placed 50 over the forgings and welded thereto. Thus the two upwardly extending elbows of the cylinder head and their bosses 23 are connected together by the sheet metal jacket thereby forming a rigid connection between 55 the two elbows.

It will be readily seen that this construction is light, strong and rigid and may be easily, quickly and accurately manufactured, the entire cylinder head and inlet and exhaust elbows being formed from a single drop forging. The compression space or compression chamber in the cylinder head 60 can be very accurately machined and, there-

fore, the volume can be accurately determined as the head may be machined before 65 it is welded to the cylinder.

While I have in the above specification described one embodiment of my invention, it should be understood that the invention is capable of modification and that modifications and changes may be made without departing from the spirit and scope of the invention as expressed in the following claims.

What I claim and desire to secure by Letters Patent is:

1. A cylinder unit comprising in combination a cylinder barrel, a cylinder head forging having an integrally formed combustion chamber and inlet and exhaust elbows and valve stem guiding members, means for bracing said valve stem guiding members and flanges carried by said barrel, said combustion chamber, said elbows and said bracing means for the valve stem guiding members and a water jacket welded to said flanges.

2. A cylinder unit comprising a barrel having a laterally extending flange adjacent its upper end, a cylinder head having a laterally extending flange adjacent its lower end, means including an annular recess in the head whereby said head may be positioned on said barrel with said flanges in proximity to each other in position to be welded together.

3. A cylinder unit comprising a barrel having a flange extending laterally therefrom and spaced from the upper end thereof, a head having a flange extending laterally from its lower edge and adapted to be welded to said first named flange, said head having an annular recess adjacent its lower edge adapted to engage the upper edge of said barrel to properly position said cylinder head on said barrel.

4. In a cylinder for hydrocarbon motors, a conduit forged integrally therewith and a valve stem guiding member forged integral with said conduit and extending downwardly into said conduit with a water space 110 surrounding it.

5. In a cylinder head for hydrocarbon motors, a valve stem guiding member forged integral with said head, a lug forged integral with said head and bracing means rigidly connecting said lug and said guiding member.

6. In a cylinder head, a plurality of integrally forged valve stem guiding members, integrally forged cam shaft and housing, supports carried by said head and means connected to said supports and said members for bracing said members and supporting a water jacket cover for said head.

In testimony whereof I affix my signature.
HENRY MARTIN SCOVEL.
